UNITED STATES PATENT OFFICE

JARVIS C. MARBLE, OF MOUNT VERNON, NEW YORK, ASSIGNOR TO AMERICAN
THROTTLE COMPANY, INC., OF NEW YORK, N. Y.

VALVE

Application filed March 21, 1928. Serial No. 263,575.

This invention relates to multiple throttle valves of the type disclosed in United States Patent #1,662,955 granted March 20, 1928, to R. M. Brown, and is in the nature of an improvement upon such valves.

In the type of throttle valve with which the present invention is concerned, difficulty has been experienced in the operation under certain conditions which produce a state of unbalance of the valves, tending to make them fly open and either throwing a strain on the throttle-operating mechanism if there is a fixed connection between the valves and such mechanism, or causing the valves to jump away from the lifting mechanism when the latter is not positively connected thereto.

The object of the present invention is to provide an improved form of the arrangement shown in the above patent in which any tendency of the valves to become unbalanced is eliminated. Other and more detailed objects of the invention will become apparent from the ensuing description of a preferred form illustrated in the accompanying drawings, in which Fig. 1 is a fragmentary longitudinal section through a superheater header in which the improved form of valve is incorporated; Fig. 2 is a section through the header taken at right angles to Fig. 1, and Fig. 3 is a fragmentary section similar to Fig. 2 and showing another form of valve.

Referring now to Figs. 1 and 2, the superheater comprises a header casting indicated generally at 1, located in the usual position within the smoke-box 2 of the locomotive and of the same general form as that shown in the patent referred to above. Steam enters the saturated steam chamber 1a from the boiler dry-pipe 3, and after passing through the superheater elements 4 located in the boiler flues is delivered through the passages 5 to the chamber 6 of the superheated steam header 7. The header 7 is divided by longitudinal partitions 8 and 9 to form the upper or inlet chamber 6 an intermediate outlet chamber 10, from which the engine steam pipes 11 lead, and a lower closed balancing chamber 12. Chambers 6 and 12 are placed in communication through the port 13 controlled by pilot valve 14.

A plurality of ports 15 having valve seats formed at their upper circumferences provide communication between chambers 6 and 10, these ports being controlled by poppet valves 16 having upwardly extending stems 55 guided in the caps 17.

In alignment with each of the valve ports 15 in partition 8 are the ports 18 in partition 9, these ports being substantially of the same diameter as the ports 15. The partition 9 around each of these ports is thickened so that the walls of the ports 18 form short open-ended cylinders, the upper portions of which are provided with a plurality of vertical slots 19 extending for some distance below the tops of the cylinders. The valves 16 are provided with stems extending through chamber 10 into chamber 12, and pistons 20 are either attached to or formed integrally with the valve stems, said pistons being a sliding fit in the ports 18. The lower ends of the valve stems are provided with spaced flanges 21 between which the cam fingers 22 of cam shaft 23 are located. The cam shaft 23 is carried through the end of the header to the exterior of the smoke-box where it is attached by means of the operating lever 24 to any suitable form of throttle rigging, not shown.

As will be obvious from Fig. 2, rotation of the cam shaft 23 in a counter clockwise direction will operate to open both the pilot valve 14 and the main valves 16, the arrangement of the cam fingers 22 being such that the pilot valve is lifted from its seat first, thus placing chambers 6 and 12 in communication and through the pressure exerted below pistons 20 balancing the main valves 16. The main valves 16 are opened, preferably in succession as indicated in Fig. 1, by further rotation of the cam shaft.

As is to be particularly noted from Fig. 1, the location of the pistons 20 with respect to the slots 19 is such that when the valves 16 are seated, the pistons 20 close communication between the balancing chamber 12 and the outlet chamber 10, but as the valves are opened the pistons 20 uncover the lower ends of the slots 19 to provide a passage connecting chamber 12 with chamber 10 before the valves reach their fully opened position.

This feature of the construction constitutes the principal feature of the invention and prevents the tendency of the main valves to become unbalanced for reasons believed to be as follows:

Unbalanced pressures on the valves tending to lift them have been found to exist only in installations, notably in Mallet locomotives, where the volume of the steam pipes 10 between the throttle valve and the steam chests is relatively large. Where such conditions exist a relatively large volume of steam must be admitted to chamber 10 before the pressure therein is built up to a pressure 15 of the same order as that existing in the inlet chamber 6 and the balancing chamber 12. Therefore, when the first main valve to be opened reaches the position substantially that as indicated by valve *a*, the chamber 10 is still 20 at a materially lower pressure than the pressures existing in chambers 6 and 12. A pressure drop therefore exists between chambers 6 and 10 and when the valve is in its closed position or very nearly closed position, the 25 underside of the head of valve 16 and the upper face of piston 20 are subjected to substantially the same pressure, i. e. the pressure in chamber 10, while the upper face of the head of valve 16 and the lower face of piston 30 20 are subjected to the same pressure, i. e. that existing in chambers 6 and 12. Under these conditions the valve is balanced.

However, when the valve is moved slightly 35 above the position shown for valve *a* in Fig. 1, the head of the valve is then entirely within the chamber 6 and above the line of pressure drop between chambers 6 and 10, which is substantially in the plane of the valve seat. Under these conditions both the upper and 40 lower faces of the head of the valve are subjected to the same pressure, while the piston 20 is exposed on its lower face to the high pressure in the balancing chamber 12 and on its upper face to the pressure in chamber 10, 45 which because of the relatively small amount of steam admitted through one partially open valve is still at a pressure materially below that in chamber 12. Obviously this produces a condition of unbalance in the valve 16 50 which, if unrestrained, would be forced immediately to its fully open position by the steam pressure acting below piston 20. When the valve is held to the cam arms in the manner indicated, the tendency of the valve to 55 be forced wide open by the unbalanced steam pressure causes an undesirable force to be transmitted through the throttle rigging, tending to force the latter to open throttle position, and unless this tendency is resisted 60 manually by the operator, the throttle will be forced open. If there is no positive connection between the cam and the valve stem, as in the form shown in the patent referred to, the unbalanced pressure will cause the valve to 65 leave the cam and fly to full open position.

From the preceding analysis it will be apparent then that in the initial stages of opening the prior form of valve is balanced, but after reaching a certain opening this condition of balance in some instances ceases to 70 exist and the valve becomes unbalanced. According to the present invention, this undesirable condition is eliminated by the provision of venting means by which the chamber 12 is partially vented to chamber 10 after 75 the first main valve has been raised to a predetermined point where it would otherwise tend to become unbalanced. This venting of the chamber 12 not only tends to reduce the pressure therein but also assists in raising 80 the pressure in chamber 10, thereby tending to equalize pressures on the pistons 20, but due to the fact that the valve 14 is opened, additional steam is admitted to the chamber 12 so that a pressure of some magnitude is 85 always present in chamber 12 even after one or more of the main valves have been opened to a point where the venting slots 19 are uncovered.

An alternative form is shown in Fig. 3 in 90 which the piston 20' is provided with a number of arcuate recesses 25 which extend from the lower face of the piston to a point below the upper face thereof. In this form the ports 18 are not slotted as in the form heretofore described, and the venting of chamber 12' to chamber 10' is accomplished through the recesses 25 in the piston which provide a passage between the two chambers as soon as the valve is lifted to a point where the 100 upper faces of the recesses move to a point above the walls of the port 18'.

It will be obvious to those skilled in the art that the form and arrangement of the apparatus herein disclosed may be varied considerably without departing from the invention, as defined in the appended claims, which accomplishes the desired object by changing the pressures acting on a valve balancing means before the valve is moved from a closed 110 to a fully open position.

I claim:

1. In apparatus of the class described, a casing forming an inlet chamber, an outlet chamber and a balancing chamber, a valve 115 controlling communication between the inlet and the outlet chamber and opening against pressure in the inlet chamber, a valve balancing piston between the outlet chamber and the balancing chamber, means for admitting steam to the balancing chamber, and means for venting the balancing chamber to the outlet chamber past the balancing piston before the valve reaches its fully opened position.

2. In apparatus of the class described, a casing forming an inlet chamber, an outlet chamber and a balancing chamber, aligned ports providing communication between the inlet and the outlet chambers and the outlet and the balancing chambers, a valve control- 120

- ling the first of said ports and opening into said inlet chamber, said valve being provided with a balancing piston located in the second of said ports, means for admitting steam to the balancing chamber before said valve is opened, and means for relieving the pressure in said balancing chamber when once the valve has been moved fairly off its seat and before it is moved to fully opened position.
- 10 3. In apparatus of the class described, a superheater header comprising a steam inlet chamber, an outlet chamber and a balancing chamber, a plurality of ports providing communication between said first two chambers and a plurality of corresponding aligned ports providing communication between said last two chambers, valves controlling said first named ports, said valves comprising balancing pistons controlling said last named ports
- 15 20 and closing the same when the valves are in closed position, a pilot valve for admitting steam from the inlet chamber to the balancing chamber, means for initially opening said pilot valve, and means for subsequently opening said plurality of valves, said pistons being arranged to provide a plurality of passages connecting the balancing chamber and the outlet chamber before said valves reach their fully opened position.
- 25 30 4. In apparatus of the class described, a superheater header comprising a steam inlet chamber, an outlet chamber and a balancing chamber, a port providing communication between said first two chambers, a second port in alignment therewith providing communication between said last two chambers, a poppet valve controlling said first named port and opening into said first named chamber, said valve having a stem forming a balancing
- 35 40 piston located in said last named port, the lower circumferential portion of said piston being recessed and the piston being so located that when the valve is in its closed position the piston closes said last named port and when the valve is lifted from its closed position communication is established between the balancing and the outlet chambers through the recessed portion of said piston.
